UNITED STATES PATENT OFFICE.

SIMEON WELCH, OF MERKEL, TEXAS.

POULTRY-NEST.

No. 896,258.

Specification of Letters Patent.

Patented Aug. 18, 1908.

Application filed March 24, 1908. Serial No. 422,958.

To all whom it may concern:

Be it known that I, SIMEON WELCH, a citizen of the United States, residing at Merkel, in the county of Taylor and State of Texas, have invented a new and useful Poultry-Nest, of which the following is a specification.

This invention relates to a nest box for poultry; the object of which is to provide a strong, simple structure containing compartments for nests in which hens may lay their eggs. These compartments or nests are separated by a transverse passage-way there being openings from said passage-way into the compartments. There is also provided means for opening the compartments to remove the eggs and easily and thoroughly clean the nests from dirt and vermin.

With these and other objects in view the invention comprises the novel construction, combination and arrangement of parts hereinafter described and claimed and illustrated in the accompanying drawing in which—

Figure 1 is a perspective view of the structure open for the removal of eggs or cleaning; and Fig. 2 a vertical cross sectional view of the same on the line 2—2. Fig. 3 is a perspective view of a modified construction illustrating a connected series of nests.

Similar reference numerals are used for like parts in all figures.

In the drawing, the numeral 1 indicates the nest box as a whole and comprises an elongated rectangular structure with a flat bottom or floor 2, vertical front and back walls 3 and 4 respectively, and vertical end walls 5 which are made higher at a point preferably in front of the center, from which point the upper edges of the ends slope downward to the front and rear edges for supporting the roof of the structure. The rear slope of the roof is made of a board or boards 6 immovably secured to the nest box, to which is hinged at the peak of the roof, a door 7 that, when closed, forms the front slope.

Within the structure are placed transverse partitions 8 dividing the interior into three compartments, a central passageway 9 and a wider nest box 10 on each side of the passageway. Openings 11 are made in the rear of each partition for the fowls to pass into and out of the nests. The nest box 1 is supported above the ground by corner legs 12 of

any length which preferably project into the box and extend nearly to the roof, thereby giving the structure greater strength as the 55 sides of the box are nailed to them. A step 13 projects in front of the passage-way for the convenience of the hens entering the nests. The door 7 is held closed by any suitable fastening, a hook 14 and eye 15 is represented in the drawing, but a lock may be applied where there is danger of the nests being robbed. Ventilation is secured by holes 16 bored in the front, back and ends of the box. The door 7 is kept closed except at such 65 times as is necessary to remove the eggs and to clean out the nests.

It is to be noted that the nest box as described although complete in itself, may form only a unit in a series of nests and 70 passage-ways by extending the front, and rear walls, the floor and the roof endwise and place therein partitions similar to those described. It is preferred however to make the units separate as they are more easily 75 handled and can, in many cases, be disposed to better advantage than a large structure containing many nests.

Having described my invention, what I claim as new and desire to secure by Letters 80 Patent is:

1. A nest box comprising a roofed structure having a part of its roof hinged to form a door, and transverse partitions therein having openings through the rear edges 85 thereof, said partitions dividing the nest box into a central passage-way and two nests communicating with said passage-way through the openings in said partitions.

2. A nest box comprising a roofed structure containing a straight transverse passage-way and a nest on each side, partitions separating the passage-way from said nests and having openings therein at the rear to form entrances to said nests, and a door 95 forming a part of the roof through which access may be had to said nests.

3. A nest box comprising a rectangular box-like structure the front, rear and end walls having ventilating holes therethrough, a two 100 part roof said parts sloping in opposite directions, one of said parts being fixed and the other part hinged thereto, transverse partitions within said nest box dividing the same

into passage-ways and nests, each passage-way communicating with a nest on either side through an opening in the rear of said partitions, and supporting legs at the corners 5 of the nest box extending thereinto and downwardly below the bottom thereof.

In testimony that I claim the foregoing as

my own, I have hereto affixed my signature in the presence of two witnesses.

SIMEON WELCH.
